UNITED STATES PATENT OFFICE.

MATTHEW J. KIVLIN, OF KINGSVILLE, TEXAS.

COURSE DIRECTOR FOR FLIES.

Application filed September 11, 1922. Serial No. 587,430.

To all whom it may concern:

Be it known that I, MATTHEW J. KIVLIN, a citizen of the United States, residing at Kingsville, in the county of Kleberg and State of Texas, have invented certain new and useful Improvements in Course Directors for Flies, of which the following is a specification, reference being had to the accompanying drawings.

10 It has been found that in opening screen doors, there is a draft or suction around the jamb of the door opening, that is to say preceding and following the person passing through the door opening, and this draft or suction causes flies to take a corresponding course. This being the case, the present invention has for its purpose the provision of a course director adapted for application upon and adjacent the jamb of the door opening, that is to say adjacent where the screen door opens, so that when the draft or suction draws or causes the flies to follow the course of the suction or draft, the director or guide will act to govern the course 25 of the flies and keep them from passing through the door opening.

Another purpose is the provision of a director or guide comprising a frame consisting of a plurality of pieces connected by a plurality of perpendicular strips, there being a screen covering over the frame, acting to prevent the flies from passing through the door opening.

Another purpose is to provide a frame 35 which may be constructed of metal as well as of wood, and in this case the horizontal pieces may be made of sheet metal with lateral flanges on the arcuate edges thereof, between which and half round pieces, vertical bars and the wire mesh or screen may be secured by rivets or other suitable means.

It is to be understood that the particulars herein given are in no way limitative and that while still keeping within the scope of 45 the invention, any desired modifications of detail and desired proportions may be made in the apparatus according to circumstances.

The invention comprises further features 50 and combination of parts, as will be herein-after set forth, shown in the drawings and claimed.

In the drawings:—

Figure 1 is a perspective view showing 55 the course director for flies as applied to the jamb of the door;

Figure 2 is a horizontal sectional view on line 2—2 of Figure 1;

Figure 3 is an enlarged detail view of the course director, showing the same constructed of wood;

Figure 4 is a view similar to Figure 3 showing the course director constructed of metal;

Figure 5 is a sectional view on line 5—5 of Figure 4;

Referring to the drawings, 1 designates the frame of the course director, which comprises a plurality of horizontally arranged pieces 2, which may be any suitable proportions and shape, preferably as shown. In fact the pieces 2 have arcuate edges 3, which are opposite the straight edges 4. The ends of the pieces 2 have short edges 5, which extend at obtuse angles to the edges 4. These edges 5 are designed for the purpose of holding the course director in proper position relatively to the door jamb, in fact at an acute angle thereto, as shown clearly in Figure 2. Connecting the pieces 2 are vertical strips 6, which are secured in recesses 7 of the arcuate edges of the pieces 2. The frame is covered with suitable wire fabric or mesh work 8, the mesh work conforming to the arcuate edges of the pieces 2, so as to guide or direct the flies away from the door opening. As previously stated it has been found that there is a draft or suction around the door jamb, 75

when opening the screen door, and the flies or mosquitoes in endeavoring to pass through the door, will follow or be drawn into this draft or suction, and therefore pass through the door opening, that is to say preceding the person who passes 90 through the door opening. With the present construction of device as applied to the jamb of the door opening, the flies when drawn in by this draft or suction will abut against the interior of the arcuate screening or wire mesh work, and thereby be prevented from passing through the door opening.

In Figures 4 and 5 the frame is constructed of metal. In fact the pieces 2 are 105 made of sheet metal, and have their arcuate edges provided with lateral flanges 10, to which the vertical reinforcing bars 11 are riveted or otherwise secured as at 15, and arranged between the bars 11 and pieces 12 is wire fabric or mesh work 12.

The course director for flies in Figures 4

and 5 is identical with the course director in Figures 1 to 3 inclusive, with the exception that the device in Figures 4 and 5 is constructed of metal. Two forms of devices 5 are identical in use, and as previously stated are applied to the door frame with one edge adjacent the edge of the door, in such a position as to permit the screen door to open, and yet be able to direct the course of the 10 flies or mosquitoes or similar insects.

The invention having been set forth, what is claimed is:—

1. The combination with the jamb of a door frame, of a course director secured to 15 the exterior face of the jamb, said course director comprising a frame having an arcuate wire fabric wall curved in a direction from the jamb toward the door, and adapted to stop the flies when endeavoring to follow the 20 suction which is created when opening the door.

2. The combination with a door frame including a door jamb, of a course director comprising a frame secured to the exterior 25 face of the jamb and arranged and disposed at an acute angle thereto, said frame having a wire fabric covering of arcuate shape curved in a direction from the jamb and toward the edge of the door.

3. The combination with a door frame including a door jamb, of a course director comprising a frame secured to the exterior 30

face of the jamb and arranged and disposed at an acute angle thereto, said frame having a wire fabric covering of arcuate shape 35 curved in a direction from the jamb and toward the edge of the door, said frame comprising a plurality of horizontally disposed flanged metal pieces, vertically disposed bars secured to the flanges of and rigidly connecting said pieces so as to secure the wire fabric of the course director to the frame.

4. The combination with a swingingly mounted door and its frame, of a course director for flies in stationary relation to said frame and extending laterally from the latter in the direction in which the door moves when opening, said course director including a screen extending from top to bottom 45 of the door.

5. The combination with a swingingly mounted door and its frame, of a course director for flies in stationary relation to said frame and extending laterally from the latter in the direction in which the door moves when opening, said course director including a screen extending from top to bottom 50 of the door and being of arcuate form in cross section with the curvature of the same extending toward the door.

In testimony whereof I hereunto affix my signature.

MATTHEW J. KIVLIN.
